8 Claims. (Cl. 315—12)

1

The present invention refers to a novel type of thermionic tube in which the transfer characteristic between the input and the output is shaped at will by means hereinafter called response forming means provided in a forming zone or chamber included in the structure of the tube.

This tube allows of the performance, with a given tension which is a function of time, of all kinds of operation, including such important ones as multiplication, division, modulation, detection, limitation, squaring, taking the square root, or the sine, and the like. Hence, the novel tube permits of the performance of all the operations of which a classical thermionic valve is capable, but, as will hereinafter appear, with much greater simplicity and perfection, as well as enabling other operations to be carried out which cannot be effected by classical valves or any combination thereof.

The present method uses electron beams of which the intensity and the path of propagation can be controlled in order to realize a desired effect.

Attempts have been made in the past to use this idea, but the embodiments hitherto based on it have been most frequently adaptations of the common type of valve. The concentration was prepared by means of ordinary grids, that is to say, electrodes placed in the beam, by a suitable adjustment of the tensions, and the electrons were collected on anodes which were also of the ordinary type.

Indeed, most tubes of the prior art may be said to be merely improvements on the classical valve, obtained by applying in varying degrees the principles of electronic optics.

Thermionic tubes are also known in which a beam of electrons is produced near one end of the tube by means of an assembly generally referred to as an electron gun, the beam being directed towards the other end of the tube where a suitable target or anode is provided. Various kinds of motion have been impressed on such a beam by electrostatic and/or electromagnetic control means located to provide about the path of the beam a suitably varying field. It has also been proposed to provide special targets, as for instance, targets consisting of a plurality of elements adapted to be connected in a circuit external to the tube, in such a manner that the passage of the electron beam from one element to another will give rise to certain predetermined effects in such external circuits. It has also heretofore been proposed to interpose a so-called

2

diaphragm in the path of the cathode discharge at a point in the neighborhood of the target, particularly in connection with discharge tubes containing a rarified filling of a gas or a vapor. Such diaphragms have been used, however, merely for the purposes of selecting a small fraction of a discharge of considerable cross sectional area, so that the target is struck by a highly limited bundle of rays. Evidently in such cases movement of the general discharge in a direction transversely of the direction of propagation, before the general discharge reaches the diaphragm, will have substantially no effect on the properties of the restricted beam passing through the diaphragm.

In contradistinction to the devices of the prior art, the novel thermionic tube of the present invention may be said to depend in addition to a more systematic application of the principles 20 of electronic optics and of the idea of controlling propagation paths, on the novelty of introducing special response forming means whereby a tube is obtained which has entirely new and highly useful properties.

As hereinabove indicated, the novel thermionic tube of the present invention is adapted to produce an output which shall be any predetermined desired function of an electrical quantity impressed on the device as a control factor, said 30 tube consisting in an electron discharge device of the kind comprising a means for producing an electron beam of desired cross section with control means in the path of the beam and non-accelerating control means positioned in operative 35 relationship with respect to said beam, said tube including on the side of said control means remote from said source and in the path of the beam, a response forming system the composition and geometry of which may be designed at 40 will for causing under the influence of the preceding controls, the magnitude of the current of electrons issuing from the response forming system to be proportional to said predetermined desired function, said tube further including an 45 electrode, generally a passive electrode, disposed to collect the electrons issuing from the response forming system.

The idea to be stressed is that any arbitrary type of response function desired can be precisely obtained by the mere adjustment of the chemico-geometric structure of the surface of solid bodies. Besides, the use of trajectory control by fields which do not exchange energy with the beam abolishes the finite charge which usual 55 tubes present to their input circuits, and the pos-

sible use of a passive collector whose eventual variations of potential do not change the output current, will furnish a device with infinite internal resistance which abolishes the ordinary limitation of the supplied current by the output circuit.

These and other objects and advantages of the present invention will become more clearly apparent in the course of the following description in which reference is had to the accompanying drawings.

In the drawings:

Fig. 1 is a diagram illustrating the principal operative portions of a thermionic tube according to the present invention.

Fig. 2 is a diagrammatic representation of one embodiment of the novel tube.

Fig. 3 is a diagram illustrating another embodiment of the tube.

Fig. 4 is a diagram illustrating a tube combining the features of the response forming systems of the Figs. 2 and 3.

Fig. 5 is a diagram illustrating the principles of intensity control by electron optical methods.

Fig. 6 is a diagram illustrating the formation of the output by electron optical control of the beam.

Fig. 7 is a diagram representing the cross section of an electron beam in relationship with one type of response forming element.

Figs. 8 and 9 are graphs representing the characteristic curves of certain parts of the new tube.

Fig. 10 is a diagram illustrating how the geometry of the response forming system may be determined in a given case.

Fig. 11 is a diagram illustrating the operation of one type of response forming member.

Figs. 12 and 13 are graphs representing respectively the output current characteristic, and the family of curves equivalent to the plate characteristic of an ordinary valve, as obtained from a tube of the present invention having a given response forming system.

Figs. 14 and 15 are diagrams illustrating the formation of sinusoidal functions by reflection.

Figs. 16 and 17 are diagrams illustrating the formation of sinusoidal functions by barrier.

Figs. 18 and 19 are diagrams illustrating alternative arrangements for obtaining square-topped waves.

Fig. 20 is a diagram showing forming means adapted to the detection of amplitude modulation.

Figs. 21 and 22 are diagrams illustrating the formation of saw-tooth outputs.

Fig. 23 is a perspective view of a modified response forming means adapted to give a saw-tooth output.

Fig. 24 is a graph illustrating the output obtained by the means of Fig. 23, and

Figs. 25 and 26 are diagrams illustrating further modifications.

Referring first to Fig. 1, the novel tube comprises an envelope 10 of glass enclosing a well evacuated space. At one end of the tube is suitably mounted a source of a stream of electrons, which may be of any well known type. For example, it may comprise an indirectly heated cathode 12, a heating filament 14, an intensity control grid 16 and beam concentration means 18, so arranged that from said beam concentration means there issues a beam of electrons having a desired cross section. The tube likewise comprises non-accelerating control or deflecting means indicated by the general reference number

20 and disposed on the side of the beam concentrating means 18 remote from the source 12, 14, and 16. Said deflecting means 20 is adapted to have impressed upon it a variable electrical quantity v , whereby the electron beam may be deflected either along the x -axis or along the y -axis or in both said directions simultaneously, the axes of coordinates being shown in the figure with the z -axis extending longitudinally of the tube. In other words, the beam of electrons is adapted to be deflected either height-wise or width-wise of the tube or both height-wise and width-wise thereof.

On the side of the deflecting means 20 remote from the source, we provide a response forming system indicated by the general reference number 22, which is positioned in the path of the beam emerging from the control zone defined by said deflecting means. We further provide a target, or rather, a passive electrode 24, located so as to collect the electrons issuing from the forming system.

The response forming system itself, while always depending for its operation on its composition and geometry may be adapted to any actual constitution of the electron beam and, may be embodied in one of two principal ways or as a combination of such principal ways. It may, for example, be embodied as a barrier having an opening adapted to be explored by the electron beam moving in response to variations in the controlling quantity v , so that the cross sectional area of the beam which passes beyond the barrier, that is the amount of output current, shall vary in accordance with the shape of the opening.

Alternatively, we may use as a response forming member, a surface having secondary emission properties of such a nature that when the surface is explored by the beam moving in response to the controlling quantity v , the secondary emission shall vary in accordance with the chemico-geometrical structure of the surface at the point of incidence.

Obviously we may combine these two types of response forming members and may shape the beam by means of a barrier before allowing it to impinge on the secondary emission surface.

As will be clear from the above general indications, and as will hereinafter be explained in detail, the response forming system may be designed so that the composition of the members thereof is neutral or inoperative for the purposes of forming and only the geometry of said members constitutes the forming factor. The system may also be designed so that the chemical composition of said members, e. g. as secondary emission surfaces, is the forming factor the geometry of the surfaces being so chosen as to be non-contributive at all points thereof. Furthermore, between these broad limits any combination in which both the geometry and the chemical composition of the members enter as forming factors to a greater or less extent, may be utilized.

The beam may move across the response forming member as a whole or the beam may be expanded and contracted transversely of its direction of propagation to secure variation of the intensity modified by the geometry and/or composition of the forming member. Both these methods of securing the formation of the response characteristic are in the present specification to be understood as included in the term "exploration." Also it should be noted that the

term "non-accelerating" as applied to the control means, relates to acceleration in the direction of propagation of the beam as a whole so that some transverse acceleration may be present.

From the foregoing general description it will readily be seen that the novel tube is susceptible in operation of a large number of adjustments and controls, which may be summarized as follows:

- (a) Control, called "electric," of the intensity of the current in the beam by the tension applied to the grid.
- (b) Control, called "geometric," of the displacements of the beam by one or more tensions or currents applied to the deflection means.
- (c) Control, called "optic," of the width of the cross-section of the beam by one or more tensions applied to the concentration means.
- (d) Control of the sensitivity of the deviation means by one or more tensions applied to the concentration means.
- (e) Adjustment of the law which relates the deflection with the deflecting signals by the design of the deflecting means and deflecting chamber.
- (f) Adjustment of the law which relates the deflection with the response by the design of the interposed response forming means, the latter being of the general type of opened barrier, or reflecting surface, or a combination of the two.

The last adjustment, which constitutes the essence of the present invention, will be referred to, as response "forming."

Obviously, two or more of these controlling or adjusting factors may be used simultaneously, and the type of control or adjustment then obtained is most suitably indicated by a combination of the terms indicating the constituent adjustments.

The combination of the two principles of controlling the movements of the beam by means located outside the path of the beam, creating fields in quadrature with the beam, and of the shaping of the output by means of geometrical response forming systems, establishes a general basis for the construction and design of tubes adapted to give a predetermined result or type of operation, without the necessity of inventing a suitable tube for each several application. As will be seen below, the response forming system may readily be designed for any type of desired functional relationship between the output and the controlling quantity.

Certain embodiments and applications of the novel tube will now be described and for simplicity the majority of these embodiments will be described in terms of one or other design of response forming elements, but it is to be understood that, in general, alternative designs may be used with equal facility for the same purpose. Thus a barrier with a specific opening may be replaced by or combined with a secondary emission surface of a specific chemico-geometrical structure, and vice versa. All such alternatives are held to lie within the scope of the present invention.

In Fig. 2, we have shown an embodiment of the tube in which the response forming system is of the barrier type. In this embodiment the grid 16a and beam concentrating means 18a are shown adapted to produce a beam of circular cross section, but it should be clearly un-

derstood that any other suitable cross section of electron beam may be employed. The forming system 22a consists of a plate 26 having an aperture 28 formed therein, the plate being so arranged that the aperture is disposed in the path of the beam between the deflecting electrodes 20a and the passive collector electrode 24a. The gap or aperture 28 varies in width height-wise of the tube, and the control electrodes 20a are adapted to deflect the beam height-wise or along the x -axis. It is obvious from the figure that as the beam is caused to explore the aperture 28, the section of the beam passing through said aperture and therefore adapted to be received by the collector 24a, varies in response to the varying deflection of the beam.

It will be clear to those skilled in the art that more accurate or well defined results will be obtained if a beam is used having a substantially rectangular cross section of width large compared with its height. Such a beam may conveniently be termed laminiform and may be obtained either by electron-optical means or else by periodically displacing a circular section beam width-wise of the tube. The principles of the electron-optical methods for obtaining laminiform beams have already been described in the literature of the art and are held to require no further explanation here. The method of periodical displacement is subject to the limitation that the frequency of width-wise displacement must be greater than the highest frequency of the variation of the controlling quantity v .

Fig. 3 shows diagrammatically a tube according to the present invention in which the response forming system 22b is constituted by secondary emission surface 30 located in the path of the beam emerging from between the control or deflecting members 26b. The beam is prepared, as before, from the electrons issuing from the cathode 12, by means of a grid 16b and concentrating means 18b, and may be of any desired cross section. In the present instance a very fine circular cross section beam is quite suitable. The passive electrode 24b is located so as to collect the secondary electrodes emitted by the surface 30, and will therefore generally be to one side of the tube rather than at its end.

The secondary emission is, as is well known, a function of the angle θ , which the beam makes with the normal to the surface at the point of impact. Actually, the secondary emission also depends to some extent on the velocity of the primary electrons, but at the present time it is quite feasible to prepare secondary emissive surfaces such that the influence of the velocity of the primary electrons shall be within a wide range a negligible factor.

Still referring to Fig. 3, it will readily be appreciated that the geometric control, or formation of the output, is obtained by causing the beam to explore the surface 30. For every position of the beam corresponding to a value v of the control quantity, there is an angle of incidence θ depending on the shape of the surface and therefore a corresponding value of the secondary emission. The relationship between the coefficient of secondary emission and the angle of incidence θ is expressed by a well established natural law, so that said relationship is susceptible of practical application.

In Fig. 3 the surface 30 has been shown as curved only in one direction, so that in operating the tube the beam will be deflected also in only one direction, say height-wise of the tube.

It is however possible, and sometimes desirable, to provide a secondary emission surface the inclination or constitution of which varies along both the x and the y -axes, in which event additional deflection will be provided in order to enable the beam to be deflected simultaneously width-wise and height-wise of the tube so as to explore the whole of the surface.

Fig. 4 shows a combination of the construction of the response forming systems illustrated in Figs. 2 and 3. It will be noted that the barrier plate 26c with its aperture 28c is interposed in the path of the beam between the deflecting means 20c and the secondary emission surface 30c, the passive electrode 24c being positioned with respect to said surface as in the case of Fig. 3.

In Figs. 2, 3, and 4 the deflecting means has been shown as adapted to generate an electrostatic field, but it is clear that we may use electromagnetic or magnetic deflecting means, either alone or in combination with each other and/or with electrostatic means in any of the many possible embodiments of the present invention.

Instead of causing the beam as a whole to move over the aperture in a barrier member, we may produce what may be termed a transverse pulsation of the beam, by making use of electron-optical principles. In Fig. 5 is shown a diaphragm D having an opening O. If the beam, indicated by the shading, is focused, the whole of it may be caused to pass through the opening O. On the other hand, if it is defocused, or spread transversely, not only will the intensity per unit area of beam cross section be reduced, but the diaphragm D will allow only a selected portion of the beam to pass so that the intensity of the current carried by the issuing beam is also reduced. This provides an optical means of controlling the intensity of the beam which is allowed to pass on to the response forming elements, and is a method known in the art.

However, as shown in Fig. 6, we may combine this optical control with a response forming element in order to cause the beam as it pulsates to explore the forming aperture. As illustrated, the barrier 26p has a double gap 28p and the beam is adapted to be focused so as normally to strike the barrier at the junction of the two parts of the gap and to be of such cross-sectional area as to be substantially completely stopped by the barrier. On defocusing, the cross-sectional area of the beam increases as indicated by the broken concentric circles, so that the expanding beam sweeps over the aperture and simultaneously its intensity is reduced. The function of the shaped gap is therefore to produce the formation of the desired function in combination with the variation in intensity by superimposing the factor represented by the shape of the gap which allows more or less of an intensity modified beam to pass in accordance with the results desired.

The manner in which the composition and geometry of the response forming system may be designed for any given case will now be discussed. The law of the shape of the forming means, i. e. the law which has to be defined, will be, for the tube of Fig. 2, that of the variation of the width y of the aperture as a function of the height-wise displacement, that is to say of a function of x .

It is possible to control the coefficient of secondary emission not only by the relative inclination of beam and reflector, but by the variation of the chemical structure of the emissive layer.

This layer will then be prepared by more or less fine strips of selected alloys progressively changed to present any predetermined succession of values of secondary emissive force. This type of reflector can be referred to as "structural" in contradistinction to that based on the change of the angle of incidence, which can be referred to as "stereotonic." However, since all the methods of utilization are identical for these two types of reflector, the convenient simplification will be made of speaking only of the stereotonic one and of using the same words for the two. For example, the term "shaping" will be used indifferently to include a forming of the shape of the reflector or a chemical deposit on or treatment of an unformed body or an aggregate of selected alloys or any combination of these methods of controlling the coefficient of secondary emission.

Naturally, the reflector can utilize a combination of structural and stereotonic shaping.

For the tube of Fig. 3 the law will be that of the variation of the angle of incidence as a function of the displacement of the beam either width-wise or height-wise, or both, that is to say as a function of y or of x or of x and y simultaneously. For the tube of Fig. 3 but with a structural reflector instead of a stereotonic one, the law will be directly that of variation of the coefficient of secondary emission with the displacement along the surface. For the combined type of Fig. 4, the law will be the combination of the law for Fig. 2 and of the angle of incidence as a function of the height-wise displacement y .

In any given practical case the data include the function relating the output current of the tube with the electrical quantity applied to the deflecting means. This, of course, is the function it is desired to produce. On the other hand, a given deflection characteristic is chosen, that is to say, the function relating the coordinates of the position of the beam with the electrical quantity applied.

The actual designing of the tube will therefore differ slightly according to which type of tube it is desired to construct. For a tube of the type of Fig. 2, it is necessary to know a quantity which will hereinafter be called the current characteristic of the beam, or more briefly, the characteristic of the beam. In the case of Fig. 3, the quantity that must be known is the characteristic of reflection of the electron emissive surface, or more shortly, the reflection characteristic.

The definition of the term characteristic of the beam is best understood by reference to Fig. 7, which shows a cross section of a beam which is supposed to be circular. If now the beam is obstructed by a plate 32 having a slot 34 of width $2y$, which is varied, and the current passing be measured, a characteristic curve may be drawn relating said current to the half width y of the aperture 34. This curve is the one which has been termed above the characteristic of the beam.

It is obvious that the form of the beam characteristic depends on the form of the cross section of the beam and also on the distribution of intensity at the several points of the section. For example, if the cross section of the beam is a very narrow and relatively wide rectangle, and the distribution is uniform, the characteristic will be a straight line.

For other forms of beam cross section, the characteristic will be a curve which may be determined by theory or by experiment, and has the following properties: (a) It has no negative values; (b) it passes through zero; (c) its maxi-

mum value is obtained when $2y=2B$, where B is the half width of the cross section of the beam. In general the shape of the curve will be like that shown in Fig. 8, where i_m is the maximum current carried by the beam.

The reflection characteristic of the type of valve illustrated in Fig. 3, gives the secondary emission obtained from a surface as a function of the angle of incidence. By "emission" is here to be understood the coefficient b , which gives the relationship between the secondary and primary currents. If the relative values of b with respect to its maximum b_m , are drawn as ordinates we have the advantage that they are equal to the relative values of the output current, i/i_m . The characteristic has the general shape shown in Fig. 9. The principal features of this curve are (a) that it has no negative values; (b) it does not pass through zero for a normal incidence $\theta=0$, but through a minimum value b_m . Its maximum value is obtained when

$$\theta = \frac{\pi}{2}$$

that is at so-called tangent incidence. The minimum and maximum values of the current produced depend on the material composing the reflecting surface. In certain cases of semi-conductive materials $b_m=0$, but then b_m is small. With the structural type of reflector it will be easier to get a reflection characteristic which reaches zero.

When either the beam characteristic or the characteristic of reflection as well as the deflection characteristic is known, the shape of the aperture or the contour of the surface required for each application may readily be determined. The method of determination is illustrated in Figure 10, in which the left-hand half axis is used as the axis of y/B or θ according to whether the tube is of the type of Fig. 2 or Fig. 3. In quadrant I the function it is desired to form with the tube is graphed, and this function has been shown in the form $i/i_m=f(v/v_0)$, where v_0 is a certain value of reference for the geometrical control magnitude. The characteristic of deflection $x/A=\Delta(v/v_0)$ where A is a certain value of reference for the displacement, is shown in quadrant II. In the example illustrated the characteristic $x/A=\Delta(v/v_0)$ has been supposed a straight line, but when advisable its shape may be altered by a suitable arrangement of the deflecting devices.

The characteristic $i/i_m=H(y/B)$ of the beam, or the characteristic $i/i_m=G(\theta)$ of reflection is drawn in quadrant III.

The required shape of the aperture,

$$y/B=S(x/A)$$

or the law connecting the angle of incidence with the coordinate x , $\theta=\Sigma(x/A)$ is constructed point by point in the following manner. Any point M_1 is taken on the curve of quadrant I and from it lines are drawn parallel to the axes to cut the curves in quadrants II and III at points M_{11} and M_{111} respectively, from which parallels are drawn to M_1M_{11} and M_1M_{111} respectively to cut each other at M_{111} which will be a point on the required curve. In the case of a tube of the type of Fig. 3, this method only gives the equation of incidence $\theta=\Sigma(x/A)$, but from this equation the surface contour can be deduced by methods well known in elementary geometry. For a tube of the type shown in Fig. 4, quadrant I will contain not a single curve, but a family of curves since the desired function would then be of the type of two

independent variables $f(V_1/V_{01}, V_2/V_{02})$. For each curve the construction described above is repeated so that in quadrant IV another family of curves is obtained which defines the reflecting surface.

Some of the innumerable applications of the novel tube will now be described in broad terms and it should be noted that in all of these applications the shapes of the apertures and/or surfaces have been determined according to the method just described.

The novel tube may be used as an amplifier. The response forming element (aperture and/or reflecting surface) may be designed so that the output current i as a function of the geometric control voltage v , shall be a straight line. For example, let a tube with compound response forming elements as shown in Fig. 4 be considered and, for simplicity, suppose the surface 30c to be a plane and the beam to be laminiform. It is easy then to see that if the characteristic is to be a straight line the aperture 28d must be in the shape of a V, as shown in Fig. 11. On the other hand, for a tube of the type of Fig. 3, it can readily be shown by the methods discussed above that the profile of the reflection surface must be parabolic in shape.

Fig. 12 shows the characteristic curve of output current plotted against geometric control voltage of such a tube, and the family of curves shown in Fig. 13 is the equivalent of the plate characteristic of an ordinary valve, that is to say, to the curves obtained by plotting output current against collector voltage.

It is seen that the characteristic can be almost strictly linear and that the exactness of the linearity depends upon the accuracy with which the aperture 28b or the parabolic reflector is made. The characteristic will only depart from linearity when the beam is at the vertex of the V or in the apex of the reflector (Fig. 11). The elbow or bend in the curve of Fig. 12 will be smaller in proportion to the thinness of the laminiform electronic beam.

From Fig. 13 it may be seen that the internal resistance of the tube is practically infinite, because the collector does not affect the velocity of the primary electron in such a manner as could alter the secondary emission. Said Fig. 13 further shows that the tube has all the characteristics of an ideal pentode.

Referring again to Fig. 12, it can be seen that the tube may be used so that the position of the rest of the beam, that is to say, when $v=0$, will be such that the beam will be on the bend of the curve, in other words, hardly projecting into the V shape gap or into the responsive zone of the reflector. In this form, we also have an ideal detector which does not consume energy from the source to which it is connected.

As regards orders of magnitude there is no difficulty either. In current practice in connection with beams in television tubes, intensities of approximately 1 ma. are mentioned. Tubes are also known having a deflection sensitivity of 5 mm. per volt. On this basis, if the height of the V shape gap or of the reflector is assumed to be 1 cm. the straight portion of the transfer characteristic will already have a gradient or slope of 0.5 ma./v., on the supposition that the reflecting surface 30 has no multiplying effect. If a multiplication of five times is assumed for said surface, the slope would be 2.5 ma./v. In the reflector type of tube such an amplification is inherently present.

The tube of the present invention may also be used as a converter. If in an amplifying tube the current is controlled not only by the geometric control v , but also by the electrical control u , the output current would be strictly proportional to the product vu , provided that the excursion of u remains within the linear zone of the electrical control. If v is made the tension of a local oscillator of frequency f_1 , and u that of the signal of frequency f_s , in the output current there will be terms of frequency of f_1-f_s or f_1+f_s , which may be taken as intermediate frequencies in a classical superheterodyne.

Should there be any difficulty with respect to a want of linearity of the electrical control, a tube can be used with response forming means of the reflector type, the forming surface being so shaped that two independent geometric tension controls applied simultaneously to heightwise and widthwise deflecting means respectively, will cause the output current to be exactly proportional to the product v_1v_2 . Thus the tube provides a high signal level converter, without whistlings, interferences and deformations.

Other applications can immediately be found for the multiplying tubes as for example, as watt amplitude modulators meters, phase meters, and the like, but in the case of the tube of the present invention, such applications are effected with greater perfection, precisely because of the greater perfection of the multiplying properties of the tube.

It will be appreciated from the foregoing that one of the principal operative control factors in the novel tube is represented by electrodes lying outside the beam and by fields in quadrature with the beam, or by the optical focusing means, all of which do not accelerate but only deflect the electrons, or vary the cross-section of the beam. Consequently, the impedance of the control elements becomes practically infinite.

The following illustrative examples of various applications will make this clear.

The principles of the present invention may be utilized to provide a highly satisfactory R. M. S. voltmeter having a substantially linear scale, since said principles readily permit of the construction of one tube having a characteristic of the form $i=kv^2$, and of another having a characteristic of the form $i=kv\sqrt{v}$, which two tubes may be used in combination to give a voltmeter of the type stated. In the first, or squaring tube, the mean value of the squares of the voltage v will be obtained. This mean value would itself already be proportional to the effective value of v , but a voltmeter constructed with this tube alone would have a parabolic scale. If the output of the squaring tube is passed through the other or root extractor tube, a final output will be obtained which is proportional to the effective voltage, so that a linear law scale is achieved.

Tubes according to the present invention may also be constructed to give outputs following a sinusoidal law. Figs. 14 and 15 show two types of surfaces of secondary emission suitable for the production of an output proportional to the sine or cosine of a given angle, and Figs. 16 and 17 illustrate two types of apertures designed to give similar results in tubes of the type of Fig. 2. In each of these four figures, the electron beam EB is adapted to move widthwise of the paper in exploring the response forming member. This finds application in frequency modulation.

Another highly useful purpose to which the tubes of the present invention may be applied

is secret transmission. The use of the tube as a classical amplitude modulator has already been explained hereinabove. Such a modulator gives the product of the carrier wave $e=E \sin \omega t$ and the function of formation $\beta(v)=A+Bv$ which is exactly linear as a function of the geometrical control quantity v which reproduces the intelligence. If, as in the case of secret transmission, it is desired to modulate purposely without fidelity, it suffices to take for $\beta(v)$, where v is still the intelligence, any function which has purposely been made peculiar and complex by means of a response forming system of irregular properties. The wave $E\beta(v) \sin \omega t$ sent through the ether, then carries a completely deformed modulation, and if it is detected, a tension $u=\beta(v)$ will be obtained in which nothing of the intelligence will be recognisable. The intelligence can only be restored by a listener aware of the law $\beta(v)$ of the response forming system of the transmitter. Such listener will apply the detected tension u to the geometrical control means of a tube, the response forming system of which shall have properties of deformation exactly opposed to those of the forming system of the transmission tube, that is to say, a forming system which shall give the response law $v'=\beta'(u)$, where β' is the inverse function, in the mathematical sense, of the function β . Thus at the output of the reception tube the tension will be $v'=\beta'(\beta(v)) \equiv v$. In this manner, a secret transmission can be established by constructing two tubes with response forming systems having any arbitrary and irregular characteristics, and inverse to one another, in the sense of the inverse functions of analysis. The method is of the greatest possible simplicity and does not require circuits or adjustments. It is almost infinitely flexible, since, for example, in the barrier type of tube, two or three strokes of a file applied to the gap defining edges are sufficient to constitute a secret channel. The efficacy of the protection (secrecy) afforded, is practically complete, since the only manner in which the deformed intelligence can be restored is by using a receiving tube with a response forming system properly designed to be the counterpart of the transmission forming system.

The widening of the spectral band occupied by the modulation consequent on the deformation is not a serious obstacle, since secret transmission is generally applied only for spoken communications the spectrum proper to which is in itself narrow, and to short waves where the absolute range of frequencies available for each transmitter is great.

In Figs. 18 and 19 are shown alternative ways of obtaining square topped waves by means of tubes of the present invention. In the secondary emission type of tube shown in Fig. 18, the emissive member $30d$ is shaped so that the angle of incidence shall be constant, and in the barrier type of tube, the aperture $28d$ is made of constant width. The operation of such tubes, which can readily be understood from Figs. 18 and 19, will be briefly described for simplicity with reference only to Fig. 19. If the position of rest of the beam, that is, its position when the geometrical control quantity $v=0$, is adjusted so that it falls just below the line $a-a$, at the bottom of the aperture, then for the values of the alternating quantity applied to the geometrical control means which cause the beam to move upwards, or to oscillate within the aperture, there will be a constant output U . For those values which deflect the beam below the line $a-a$, the output will be

zero. This method allows accurately square topped waves to be obtained of frequencies considerably higher than is possible with known methods.

Fig. 20 illustrates the use of a tube of the present invention as a detector of amplitude modulation. Suppose there is an incident signal of the type $e_1 = E(t) \sin [\phi(t)]$, where the amplitude E may vary with the time as well as the argument ϕ , provided that the corresponding instantaneous frequency $\omega = d\phi/dt$ does not go beyond a limited band. If ω is fixed, $\phi = \omega t$, and we have a wave of pure amplitude modulation. If ω includes a fixed portion and a variable portion, the wave is one which issues from a frequency responsive circuit to which a frequency modulated wave has been applied. In all practical cases, the complementary signal $e_2 = E(t) \cos [\phi(t)]$ can be obtained by known means.

If these two signals e_1, e_2 , are used as geometrical control magnitudes in a suitable deviation chamber, and they be supposed substantially sinusoidal, it is readily possible to produce a conical deviation of the beam, and the trace thereof on a screen will be a circle the radius vector R of which will be proportional to the common amplitude $E(t)$ of the complementary signals e_1 , and e_2 . If such a beam is allowed to fall on a response forming system of the secondary emission type including a surface $30r$ which is a surface of revolution about the axis of the tube, as the amplitude $E(t)$ of the incident signal varies, the beam will describe circles P, P' , of varying radii on the surface $30r$. It is always possible to define immediately, by applying the general methods discussed hereinabove, a shape for the surface such that the response shall be proportional to the radius R , that is to $E(t)$. Thus an accurate detection is obtained of the variation inscribed in the amplitude of the signal, by a process which does not require any time constant. The tube does not load the circuit to which it supplies the detected output. It should also be noted that it is not essential to adjust the conical deviation of the beam accurately. Any closed and sufficiently regular path will serve as a satisfactory basis for defining a response forming system of characteristics adapted to provide detection.

Another possible application of the novel tube is the production of saw-tooth voltages or waves. If the beam is given a circular deviation of frequency ω , and it is allowed to fall on a strip separated into two portions $30e$ and $30'e$ as shown in Fig. 21, and having its surface prepared so that the secondary emission shall increase linearly as the electronic spot moves from A to B, a steadily rising output will be generated until the spot reaches the gap G, when the output is suddenly reduced to nothing, whereupon a similarly growing output is again established as the spot continues to move from B' to A'. If the currents generated by the two strips in opposition are collected, it will be seen that a saw-tooth wave of frequency 2 is generated, as shown in Fig. 22, where the points marked M indicate the maximum values at the ends B, B' of the respective strips, of the output. As in all the applications of the novel tube, the accuracy of the output function obtained does not depend on non-linear electronic phenomena, but on the accuracy with which the response forming system is constructed and on the fineness of the spot. Hence straight-line increases A—M and vertical drops M—B in the output can be obtained with much greater

accuracy than in ordinary circuits, and this holds for any frequency for which it is known how to prepare circular paths for the beam, that is to say, for frequencies much beyond the values hitherto used. The frequency of the teeth may be made other multiples of ω than 2ω , by suitably sub-dividing the strip into n equal parts where $n > 2$. It should be added that the tension which can be obtained with an output resistance of some tens of thousands of ohms is easily some tens of volts.

The saw-tooth waves may also be generated with the barrier type of tube, as illustrated in Figs. 23 and 24. For this purpose a laminiform beam will be used, as obtained by optical methods, and it will be caused to rotate in an approximately circular path so as to explore successively a pair of curved apertures $28e$ and $28'e$, which increase in width gradually in the direction of rotation of the beam. These apertures extend over diametrically opposite arcs of 90° , so that while the beam is passing over the intervening arcs there will be no output, and the general result will be as shown by the full-line curve in Fig. 24. To obtain a continuous saw-tooth wave, it is necessary to provide a second tube with the beam and the apertures $28f$, $28'f$ displaced 90° with respect to the arrangement just described, so that the second beam will produce the saw teeth shown in broken lines in Fig. 24. The two outputs are collected together to give the complete wave by connecting the outputs of the two tubes in parallel.

The tube described with reference to Fig. 19 may also be used as a silencing tube by applying the signal U_s to the grid of the electrical control and to the plates of the geometric control and adjusting the position of the rest of the beam so that it falls across the transverse center-line of the aperture. Then, so long as U_s is such that the beam oscillates between opposite ends of the aperture the signal passes in the normal way to the output circuit. As soon as the amplitude of U_s brings the beam beyond either of said ends, the output falls instantaneously to zero and remains zero for the whole time the beam remains in this position. By reason of the integrating properties of the detector such drops do not produce audible phenomena. Known art calls for the use, for obtaining this effect, of a double amplifier chain, one member of which is cut off when the peak tensions surpass a certain value.

The novel tube may also be used for automatically controlling the output. With, for example, a barrier type tube in which the aperture $28q$ is as shown in Fig. 25, output characteristics of the types represented by the curves d, e , and f , of Fig. 26 may readily be obtained. The signal is applied to the electrical control and the amplitude of the signal is detected and applied to the geometric control. The shape of the aperture $28q$ is such that as the geometric control tension v increases, the amplification between the electric control and the output varies in inverse proportionality. Hence, by suitably adjusting the position of rest (when $v=0$) of the beam to coincide with the base $b-b$ or to lie at a lower level $c-c$ (Fig. 25) then if the width of the beam be made slightly less than that of the base of the aperture $28q$, the curves d and e respectively will be obtained. If additionally the beam be made wider than the maximum width of the aperture, the curve will be like that shown at f in Fig. 26. This type of tube may be used for automatic sensitivity control by applying the rectified volt-

age proportional to the amplitude to the geometric control members with a time constant which is large compared with the slowest modulation. In this manner it is possible to obtain simultaneously a silencer between stations of adjustable threshold. If the time constant is small compared with the most rapid modulation then a demodulator is obtained which may be used as an amplitude limiter in frequency modulation receivers.

Although the present invention has been described with reference to certain embodiments illustrated in the drawings, it is to be understood that many modifications may be made in the construction and details of the tubes without departing from the spirit of the present invention, and all such modifications are held to lie within the scope of the appended claims.

We claim:

1. A thermionic tube having a response characteristic adapted to produce an output voltage proportional to a predetermined mathematical function of an electrical quantity impressed on the tube as a control factor, comprising a source of an electron beam, a non-accelerating control means positioned in operative relationship with respect to said beam for deflecting the said beam, a response forming system arranged remote from said source and in the path of the electron beam and comprising a secondary-electron emissive electrode having a geometrical configuration and surface variations producing in combination an emission response variable over the surface of the electrode and adapted to produce an issuing electronic current variable in magnitude substantially proportional to the position of the point of impact of the electron beam on the surface of the electrode, and a collector electrode arranged adjacent to said response forming system and between the said source and the secondary-electron emissive electrode for collecting secondary emissive electrons from said emissive electrode to produce an output voltage substantially proportional to the said predetermined function of the said electrical quantity impressed as a control factor.

2. A thermionic tube having a response characteristic adapted to produce an output voltage proportional to a predetermined mathematical function of an electrical quantity impressed on the tube as a control factor, comprising a source of an electron beam, a non-accelerating control means positioned in operative relationship with respect to said beam for deflecting the said beam, a response forming system arranged remote from said source and in the path of the electron beam and comprising a secondary-electron emissive electrode having a geometrical configuration producing an emissive response variable over the surface of the electrode and having a graded secondary-emission characteristic, whereby the electrode is adapted to produce an issuing electronic current variable in magnitude substantially proportional to the position of the point of impact of the electron beam on the surface of the electrode, and a collector electrode arranged adjacent to said response forming system and between the said source and the secondary-electron emissive electrode for collecting secondary emissive electrons from said emissive electrode to produce an output voltage substantially proportional to the said predetermined function of the said electrical quantity impressed as a control factor.

3. A thermionic tube having a response characteristic adapted to produce an output voltage proportional to a predetermined mathematical

function of an electrical quantity impressed on the tube as a control factor, comprising a source of an electron beam, a non-accelerating control means positioned in operative relationship with respect to said beam for deflecting the said beam, a response forming system arranged remote from said source and in the path of the electron beam and comprising a secondary-electron emissive electrode having a geometrical configuration and a graded secondary emission response characteristic producing an emission response variable over the surface of the electrode and adapted to produce an issuing electronic current variable in magnitude substantially proportional to the position of the point of impact of the electron beam on the surface of the electrode, and a collector electrode arranged adjacent to said response forming system and between said source and the said emissive electrode for collecting secondary emissive electrons from said emissive electrode to produce an output voltage substantially proportional to the said predetermined function of the said electrical quantity impressed as a control factor.

4. A thermionic tube having a response characteristic adapted to produce an output voltage proportional to a predetermined mathematical function of an electrical quantity impressed on the tube as a control factor, comprising a source of an electron beam, a non-accelerating control means positioned in operative relationship with respect to said beam for deflecting the said beam, a response forming system arranged remote from said source and comprising a secondary-electron emissive electrode disposed in the path of said beam, said secondary emissive electrode having a geometrical configuration and a secondary emissive response characteristic producing in combination an emission response variable over the surface of the electrode and adapted to produce an issuing electronic current variable in magnitude substantially proportional to the position of the point of impact of the electron beam on the surface of the electrode, and a collector electrode arranged adjacent to said response forming system and between the said source and the secondary emissive electrode for collecting secondary emissive electrons from said emissive electrode to produce an output voltage substantially proportional to the said predetermined function of the said electrical quantity impressed as a control factor.

5. A thermionic tube having a response characteristic adapted to produce an output voltage having a substantially straight line characteristic as a function of an electrical quantity impressed on the tube as a control factor, comprising a source of a beam of electrons, non-accelerating electron beam deflector means, a secondary emission electrode of substantially parabolic profile arranged at a point remote from said source and in the path of said beam, the radius of curvature of said secondary emission electrode corresponding substantially to the plane of deflection of the beam in response to said electrical quantity impressed as a control factor, and a collector electrode arranged in the proximity of the secondary emissive electrode for collecting secondary electrons issuing from said secondary electrode on being struck by said beam.

6. A thermionic device for detecting amplitude modulation of an oscillating signal voltage without limitation imposed by time constants

comprising, a source of an electron beam, two non-accelerating control means, one in quadrature with the other, arranged in succession in operative relationship with respect to the beam for deflecting the said beam, one of said control means being adapted to have impressed on it said oscillating signal voltage and the other of said control means being adapted to have impressed on it a second oscillating signal voltage in phase quadrature with the first-mentioned signal voltage to thereby move the beam in a closed substantially regular path, a secondary emissive electrode in the form of a surface of revolution about the normal path of the beam corresponding to zero values of both said signal voltages and arranged on the side of the control means remote from said source, said secondary emissive electrode having a secondary emission response characteristic substantially proportional to the radius of the surface perpendicular to said normal path, and an electrode arranged in the proximity of the secondary emissive electrode for collecting electrons emitted by the said secondary emissive electrode on being struck by said beam, whereby the variable output from said electrode is made dependent only on and proportional to the amplitude variation of the said oscillating signal voltage.

7. A thermionic tube, comprising a source of an electron beam of given cross-section, means to vary the cross-section of said beam in response to an electrical control quantity, a response forming system arranged on the side of said cross-section controlling means remote from said source and comprising a secondary emissive electrode positioned in the path of said beam, said secondary emissive electrode having a geometrical configuration and a secondary emission response characteristic adapted to vary in combination, the magnitude of the issuing electronic current substantially proportional to a predetermined mathematical function of the cross-section of said electron beam, and a collector electrode arranged adjacent to the secondary emissive electrode to collect the secondary electrons issuing from said secondary emissive electrode.

8. A thermionic device for producing a saw-tooth voltage, comprising a source of a beam of electrons, non-accelerating control means positioned in operative relationship with respect to said beam and adapted to rotate said beam in a closed substantially regular path, a plurality of secondary emission electrodes arranged in the path of said beam on the side of the control means remote from said source, each of said secondary emissive electrodes extending over a substantially equal segment of the path of the electron beam and each having a secondary emission response characteristic linearly increasing between a minimum and a maximum value, said segments being disposed around said path with the maximum emission end of one segment adjacent the minimum emission end of the next segment, and an electrode arranged to collect electrons emitted by said segments on being explored by said beam.
